UNITED STATES PATENT OFFICE

163,434

TREE DECORATING FRAME

Elizabeth M. Willis, Wheaton, Ill.

Application July 26, 1950, Serial No. 11,408

Term of patent 7 years

(Cl. D29—1)

To all whom it may concern:

Be it known that I, Elizabeth M. Willis, a citizen of the United States of America, residing at Wheaton, in the county of Du Page, State of Illinois, have invented a new, original, and ornamental Design for a Tree Decorating Frame, of which the following is a specification, reference being had to the accompanying drawing, forming part hereof.

Fig. 1 is a perspective view of a tree decorating frame, showing my new design.

Fig. 2 is a top plan view of the tree decorating frame illustrated in Fig. 1, and

Fig. 3 is a view in side elevation of the tree decorating frame illustrated in Fig. 1.

I claim:

The ornamental design for a tree decorating frame, as shown.

ELIZABETH M. WILLIS.
